CLAIM

We claim the ornamental design for a female body of a connector for fluid tubing, as shown and described.

(51) **LOC (9) Cl.** **24-02**

DESCRIPTION

(52) **U.S. Cl.** **D24/129**

This application is related to U.S. Design patent application Ser. No. 29/353,314 filed 6 Jan. 2010, and U.S. Design patent application Ser. No. 29/353,317 filed 6 Jan. 2010.

(58) **Field of Classification Search** D24/108-110.5, D24/127, 129; 285/304-321

FIG. 1 is a top-left isometric view of a female body of a connector for fluid tubing.

See application file for complete search history.

FIG. 2 is a right side elevation view of the female body of FIG. 1.
